ABSTRACT: A chain stitch forming device is provided with a movable loop retaining member for retaining a thread loop released from the loop taker of a lock stitch sewing machine. After the needle which is to be brought down next time into the thread loop held by the retaining member has passed through the throat plate, the retaining member is so actuated as to release the thread loop by a separate operating means, thus enabling a chain stitch to be formed using a lock stitch sewing machine.

CHAIN STITCH FORMING DEVICE FOR A LOCK STITCH SEWING MACHINE

This invention relates to sewing machines, and more particularly, to devices for converting a lock stitch sewing machine to a chain stitch sewing machine. A sewing machine in common use is of a lock stitch type. It has been desired that the machine be also capable of forming chain stitches, if required. Although, to meet this demand, there have been employed various types of chain stitch forming device, all of them were not only complicated in mechanism and extremely expensive, but also presented considerable difficulties in manufacture and failed to be easily fitted to the sewing machine. With some chain stitch forming device, loop taker parts of a lock stitch sewing machine, for example, a bobbin case of its retainer had to be replaced by a separate member adapted for the formation of chain stitches. This was not only troublesome to a general sewing machine user, but also most likely caused such parts to be lost after such replacement.

It is an object of the present invention to provide a chain stitch forming device wherein there is disposed a movable loop retaining member in the passage of a thread loop released from the loop taker and lifted by the takeup mechanism, thereby enabling good chain stitches to be always formed without the skipping of stitches.

A further object of the invention is to provide a chain stitch forming device wherein the aforementioned movable loop retaining member is rotatably mounted on a restraining member for obstructing the circular movement of the bobbin case retainer of the loop taker, so that said device is of very simple construction and capable of being manufactured easily and at low cost and readily fitted to the frame of the sewing machine.

A still further object of the invention is to provide a chain stitch forming device which always permits the formation of good chain stitches despite its simple construction, eliminates the necessity of replacing the bobbin in forming chain stitches as has been required for the prior art device and allows a general sewing machine user to carry out chain stitching without any troublesome operation in advance.

For a lock stitch sewing machine provided with a loop taker involving a bobbin case retainer so as to form lock stitches in cooperation with a reciprocable needle, the present invention provides a chain stitch forming device equipped with a loop retaining member for retaining a thread loop released from the loop taker, said loop retaining member being actuated by a separate operating means to release the thread loop for chain stitching after the needle has passed through the throat plate which is to be brought down next time into the thread loop held by the retaining member, so that said device eliminates the necessity of replacing the bobbin case or its retainer in performing chain stitching and can be manufactured easily and at low cost due to simple construction and always permits the formation of good chain stitches.

This invention can be more fully understood from the following detailed description when taken in connection with reference to the accompanying drawings, in which:

FIG. 1 is a perspective view of an ordinary lock stitch sewing machine permitting the use of a chain stitch forming device according to an embodiment of the present invention;

FIG. 2 is a similar perspective view of FIG. 1, showing by two dot-dash lines a frame including a loop taker rotatably mounted around a horizontal axis and extending parallel with the direction in which there is fed a work fabric;

FIG. 3 is an elevation of an entire chain stitch forming device, where a thread loop released from a loop taker is retained by a loop retaining member;

FIG. 4 is a sectional view on line 4-4 of the chain stitch forming device of FIG. 3;

FIG. 5 is a plan view of thereof; device of FIG. 3 taken from line 5-5 thereof;

FIG. 6 is a sectional view on line 6-6 of the device of FIG. 3;

FIG. 7 is a sectional view on line 7-7 of the device of FIG. 5;

FIG. 8 is a sectional view on line 8-8 of the device of FIG. 5;

FIG. 9 is a sectional view on line 9-9 of the device of FIG. 5;

FIG. 10 is a bottom plan view of the device of FIG. 7;

FIG. 11 is a perspective view of a first throat plate for lock stitching;

FIG. 12 is a perspective view of a second throat plate for chain stitching;

FIG. 13 is a bottom plan view of the second throat plate of FIG. 12;

FIG. 14 is a fragmental enlarged view of the 4-4 section of FIG. 4 where the thread loop is released and FIG. 14a is the top view of the same;

FIG. 15 is a fragmental sectional view corresponding to FIG. 3 where there is fitted the first throat plate to the frame;

FIG. 16 is a fragmental sectional view corresponding to FIG. 4 where the needle is brought down into the thread loop held by the loop retaining member to release said loop;

FIG. 17 is an enlarged view corresponding to FIG. 3 where the thread loop taken up by the loop taker is being broadened;

FIG. 18 is a side view of the device of FIG. 17; and

FIG. 19 is an enlarged view of a bobbin case retainer according to another embodiment of the invention corresponding to FIG. 14.

There will now be described by reference to the appended drawings a chain stitch forming device according to an embodiment of the present invention. A sewing machine in FIGS. 1 and 2 is an ordinary lock stitch type. A machine frame 20

comprises a cylindrical bed 22 securely mounted on a base 21, and a standard 23 rising above said bed 22 so as to support a bracket arm 24 overhanging the bed 22. In the interior of the end portion of the cylindrical bed 22 is disposed the later described loop taker. To the cylindrical bed 22 is detachably fitted a cap member 25 to allow the bobbin case to be inserted into and taken out of said bed 22. A main drive shaft 26 journaled lengthwise in the bracket arm 24 drives all the moving parts of the sewing machine and may be actuated by an electric motor (not shown) through a foot treadle or the like (not shown).

A counterbalanced crank 27 on the main shaft 26 is operatively connected through a connecting rod 28 to a needle bar 29 endwise slidable in a support 30 pivoted at 31 on the bracket arm 24 and holding at its bottom a thread-carrying eyed needle 32. A needle thread takeup lever 33 is also actuated by said crank 27 and constrained by an anchor link 34 so

as to tightly stretch and slacken the needle thread alternately in timed relationship with the endwise reciprocation of the needle 32. The passage of the needle thread extends from its source (not shown) to a thread tension device 35 through an eyelet 36 in the takeup lever 33 and then through appropriate guides such as a thread guide 37 on the needle bar 29 and finally to the needle eye. This arrangement for controlling the passage of the needle thread is typical of that which is required for the formation of lock stitches.

Numeral 38 in FIG. 4 denotes a loop taker shaft mounted on the frame 20 rotatable around a horizontal axis parallel with the direction in which there is fed a work fabric 39. To one end of the shaft 38 is fitted a loop taker 41 with a loop seizing beak 40. The loop taker shaft 38 is connected to a lower shaft 44 through a set of gears 42 and 43 (FIG. 5), said lower shaft

44 interlocking with the main drive shaft 26 by means of a timing belt 45 (FIG. 2). The loop taker 41 is designed to rotate twice each time the needle makes one reciprocation by means of the aforementioned arrangement. The needle and loop taker 41 are actuated in such timed relationship that while the needle is brought downward, the loop released from the needle eye is seized by the loop taker 41 and while the needle is lifted, the loop seized by the loop taker is released therefrom. To the loop taker 41 is supported a bobbin case retainer 47 adapted to receive an ordinary bobbin case 46. At the front upper part of the retainer 47 is formed a recess 48 adjacent to

a point through which the needle passes (FIG. 3). Numeral 49 of FIG. 5 represents a restraining member, the base end of which is fixed to the frame 20 by screws 50. At one end of the restraining member is formed a tongue 53 freely engaging the recess 48 to define an opening 52 therewith so as to permit the passage of a loop 51 released from the loop taker 41 lifted by the thread takeup mechanism, thus preventing the bobbin case retainer 47 from rotating with the loop taker 41.

Referring to FIG. 2, there is disposed in the cylindrical bed a feed dog 54 performing the known four feed motions through the slot of the later described throat plate. The feed dog advances the work fabric 39 on a work support in one direction for each endwise reciprocation of the needle 32. The feed dog 54 is fixed on a feed bar 56 connected to a feed advancing shaft 55, which is made to swing by a two-forked rod 58 so disposed as to embrace a feed cam 57 on the main shaft 26, thereby imparting forward and backward movements to the feed dog 54. The feed bar 56 is operatively connected to a swing shaft 61 which is made to swing by a rod 60 embracing a feed lift eccentric 59 fixed on the main drive shaft 26. Thus the rotation of the main shaft 26 causes the feed dog 54 to be raised. It will be appreciated that as it is conventional in the art, the linear work feeding mechanism is timed to the reciprocation of the needle so that while the needle 32 is raised above a work fabric on the throat plate, the feed dog 54 is lifted to be advanced and while the needle descends, the feed dog 54 is brought beneath the throat plate back to its original position. Numeral 62 of FIG. 1 denotes a knob for causing the feed dog 54 to perform a drop feed. Numeral 63 is a manually operable knob for controlling the advance and retraction of the feed dog 54, and numeral 64 represents a manually operable knob for controlling the amplitude of the zigzag motion of the needle.

Numeral 65 of FIG. 5 shows a loop retaining member having its intermediate portion rotatably mounted on the restraining member by a stepped screw 66. One free end of the loop retaining member 65 has a retaining section 67 for temporarily holding the released loop 51 pulled up through the opening 52 by the thread takeup mechanism. As seen from FIG. 14, one side 67a of the retaining section 67 is so formed as not to project from one lateral portion 53a of the tongue 53 of the restraining member 49 disposed on that side of the bobbin case retainer 47 to which the recess 48 is pressed as the result of the rotation of the loop taker 41. Accordingly, the loop 51 released from the loop taker 41 is lifted without being detained in the space between the aforesaid lateral portion 53a of the tongue 53 and the recess 52, always enabling good uniform chain stitches to be realized without any difficulties, for example, the slackening or resultant double formation of chain stitches.

Numeral 68 is a spring stretched between the other end of the loop retaining member 65 and the lug 70 of the fitting member 69. The spring 68 causes the loop retaining member 65 to rotate anticlockwise as shown in FIG. 5, thereby normally keeping the retaining section 67 of the loop retaining member 65 at a position above the opening 52 to hold the loop released from the loop taker 41. Numeral 71 in FIG. 14 is a groove formed at the upper part of the bobbin case retainer 47 across the recess 48 so as to extend toward both sides of the recess 48 in a sufficiently large size to receive the retaining section 67 of the loop retaining member 65. Above the groove 71 rises a projection wall 72 for guiding the loop 51 released from the loop taker 41 onto the retaining section 67 of the loop retaining member 65 so as to be securely retained thereby the projecting wall 72 has its top portion positioned lower than that side of the wall 73 of the bobbin case retainer 47 surrounding both sides of the tongue 53 of the restraining member 49 freely engaging the recess 48 through which the needle passes endwise. Therefore, the loop 51 released from the retaining section 67 is lifted by the takeup mechanism without any obstruction, preventing chain stitches from being loosened or in consequence doubly formed. Moreover, the fact that one side 67a of the retaining section 67 is so disposed

as not to project from one side 53a of the tongue 53, coupled with the aforementioned arrangement, assures the smooth feeding of the needle thread, always permitting the formation of good chain stitches. All these facts assume great significance, because there is no need for any particular machining of the parts.

The other free end of the loop retaining member 65 is bent, as shown in FIG. 3, so as to surround one end of the restraining member 49 to form a bent section 74, which contacts the underside of the restraining member 49 to prevent the loop retaining member 65 from being unnecessarily lifted. Accordingly, the retaining section 67 of the loop retaining member 65 is prevented from lifting the bobbin case retainer 47 by means of the projecting wall 72, thereby applying an excess load to the race section between the bobbin case retainer 47 and the loop taker 41. This avoids the obstructed rotation of the loop taker 41 and the occurrence of noises and wear, enabling the loop to be reliably held by the loop retaining member and chain stitches to be formed constantly.

Referring to FIG. 7, numeral 75 is an actuating plate pivoted to the restraining member 49 swingably about a pin 76 fixed to the base end of said actuating plate 75. The rising section 75a of the actuating plate is contacted by the other end of the loop retaining member 65 by the action of the spring 68, normally urging the free end 75b of the actuating plate 65 upward so as to face the underside of the feed dog 54. The actuating plate 75 is swing downward as the result of the descent of the feed dog 54 to rotate the loop retaining member 65 against the action of the spring 68, thereby allowing the loop 51 held by the loop retaining member 65 to be released therefrom by means of the thread takeup mechanism after the needle has passed through said loop 51.

A pivoting member 77 for rotatably supporting the pin 76 of the actuating plate 75 between said pivoting member 77 and the backside of the restraining member 49 is fixed, as shown in FIGS. 7, 9 and 10, to the backside of the restraining member 49 by a pair of screws 79 passing through long holes 78 perforated in the fitting member 69 and restraining member 49 in a direction perpendicular to the position in which the pin 76 is set. When the screws 79 are loosened to allow the pivoting member 77 to be slightly shifted along the long holes 78 and thereafter tightened again, then the pin 76 about which the actuating plate 75 swings is adjusted in position, thus controlling the condition of contact between the feed dog 54 and actuating plate 75 and in consequence the operating time of the loop retaining member 65 worked by the actuating plate 75, so that the operating time of the loop retaining member 65 can always be adapted for chain stitching.

Referring to FIG. 1, numeral 80 is a first throat plate detachably supported by a stepped portion 81 formed on the peripheral edge of the opening perforated in the cylindrical bed 22. As further illustrated in FIG. 11, the first throat plate 80 has a long needle aperture 82 adapted for zigzag lock stitching which extends in a direction perpendicular to that in which there is fed a work fabric, and also narrow slots 83 to allow the feed dog 54 to pass therethrough. To the underside of one end of the first throat plate 80 is fitted an elastic plate 85 to prevent said throat plate 80 from being lifted by engaging the underside of the peripheral edge of the opening of the cylindrical bed 22. The underside of the other end of the first throat plate 80 is fitted by screws 88 and 89 with an elastic plate 87 elastically engaging a projection 86 on the peripheral edge of the opening of the cylindrical bed 22. One of the screws indicated by 89 engages, as shown in FIG. 15, the actuating plate 75 when the first throat plate 80 is fitted to the frame so as to cause the actuating plate 75 to rotate up to the point (indicated by a solid line) where it is not operated as the result of the descent of the feed dog 54. Accordingly, the screw 89 constitutes a sort of stop projection for arresting the loop retaining member at a point where it can not hold the loop 51 released from the loop taker 41. Thus the lock stitch forming mechanism is brought to an operative state.

Referring to FIGS. 12 and 13, numeral 90 denotes a second throat plate detachably fitted to the frame in place of the first throat plate 80. The second throat plate has a long needle aperture 91 extending in the direction in which there is fed a work fabric. When the loop released from the loop retaining member 65 is lifted by the thread takeup mechanism, the aforesaid position of the needle aperture 91 prevents the chain stitched thread to be insufficiently tightened due to the resistance to which it is subjected while passing through the needle aperture 91. Numeral 92 is a depression formed in continuation of the needle aperture 91 to improve tightening of a chain stitched thread. The same parts of the second throat plate 90 as those of the first throat plate 80 shown in FIG. 11 are denoted by the same numerals and description thereof is omitted. The second throat plate 90 is not provided with a stop projection corresponding to the screw 89 of the first throat plate 80. Accordingly, when the second throat plate 90 is fitted to the frame, there is reestablished an operative relation between the feed dog 54 and actuating plate 75 to permit the operation of the loop retaining member 65 so as to hold the loop released from the loop taker 41. To the suspended strip 93 of the restraining member 49 is pivoted a manually operable lever 94 for disengaging the throat plate by means of a stepped screw 95 (FIG. 6). One end 96 of the lever 94 extends so as to face the underside of that part of the throat plate where the engaging elastic plate 87 is positioned, and the other end of the lever 94 constitutes an operating knob 97. Numeral 98 represents a spring stretched across the throat plate disengaging lever 94 and restraining member 49. The spring 98 causes the lever 94 to rotate anticlockwise as shown in FIG. 6. In the foregoing embodiment the restraining member 49 is fitted with all the loop retaining member 65, actuating plate 75 and throat plate disengaging lever 94. Since all these members can be arranged into a single unit, there is obtained great advantage in assembling and manufacturing a sewing machine.

There will now be described the application of a chain stitch forming device according to the aforementioned embodiment and the manner in which there are formed chain stitches. FIGS. 3 to 6 represent the state where the loop 51 released from the loop seizing beak 40 of the loop taker 41 is lifted by the thread takeup mechanism and, after passing between the tongue 53 and recess 48, is held by the retaining section 67 of the loop retaining member 65. At this time, the feed dog 54 is in a rising position and disengaged from the actuating plate 75. It will be apparent, however, that the second throat plate 90 for chain stitching is not provided with a screw 89 like the first throat plate 80, so that when the feed dog 54 descends, the actuating plate 75 is brought to an operative state.

When there is carried forward a work fabric 39 one stitch pitch by the feed dog 54, and the needle 32 is brought down again, as shown in FIG. 16, into the loop 51, then the underside of the feed dog 54 engages the free end 75b of the actuating plate 75 as the result of the descent of the feed dog 54, causing the actuating plate 75 to swing downward and in consequence the loop 51 held by the retaining section 67 to be released.

As the sewing operation goes on, a loop freshly formed by a descending needle 32 is taken up by the loop seizing beak 40 of the loop taker 41 in preparation for the formation of a succeeding chain stitch. As a fresh loop 51 is gradually broadened by the loop taker 41, the preceding loop is pulled into the work fabric 39 to form a chain stitch, as shown in FIGS. 17 and 18. Later when the feed dog 54 is lifted again, the loop retaining member 65 is brought back to its original position by the action of the spring 68 and the retaining section 67 of said member 65 is inserted into the groove 71 to be brought again to a state of holding the loop 51.

When, upon completion of the desired chain stitching, it is desired to use the sewing machine for the original lock stitching, the cap member 25 of the cylindrical bed is opened, and the knob 97 on the manually operable throat plate disengaging lever 94 is depressed with the finger to rotate the lever

94 against the action of the spring 98. Then the engaging elastic plate 87 of the second throat plate 90 is released from the projection 86, causing said plate 90 to be forcibly pushed outward. All that is required, therefore, is to remove the second throat plate 90 and instead insert the previously provided first throat plate 80 for normal lock stitching. When the first throat plate 80 is inserted, it is first guided to the stepped part 81 of the cylindrical bed 22 and the elastic plate 85 is pressed in place so as to engage the underside of the peripheral edge of the opening for said throat plate. When that part of the first throat plate 80 where the engaging elastic plate 87 is positioned is depressed, said elastic plate 87 engages the projection 86, causing the first throat plate 80 to be set in place as shown in FIG. 15. At this time the screw 89 of the first throat plate 80 engages the actuating plate 75 to swing it from the position indicated by the two-dot-dash line to that of the solid line, so that the actuating plate 75 ceases to be operated despite the movement of the feed dog 54. Therefore, the loop retaining member 65 is operated in the same manner as in chain stitching and the retaining section 67 is brought to rest, as shown in FIG. 16, independently of the loop passing through the opening between the tongue 53 and recess 48. Accordingly, the normal lock stitching can be commenced again by feeding the lower thread into the bobbin case 46.

Where it is desired to carry out chain stitching again, it is only required to replace the first throat plate 80 with the second throat plate by the same operation as used in exchanging the second for the first throat plate.

With the device according to the aforesaid embodiment, when the knob 62 is operated to bring down the feed dog 54, the actuating plate 75 swings downward to arrest the loop retaining member. Therefore, when it is desired to perform embroidery with the normal lock stitches by lowering the feed dog 54, there is no need to replace the second throat plate 90 with the first throat plate 80, but it is sufficient to operate only the knob 62.

FIG. 19 shows the part of FIG. 14 modified according to another embodiment of the invention. There is formed a groove 100 across the recess 48 so as to extend toward its both sides, and there is fitted into the groove 100 the retaining section 67 of the loop retaining member 65, the wall 101 of the groove 100 serving as the aforementioned projecting wall 72. The embodiment of FIG. 19 eliminates the necessity of forming said projecting wall 72 above the recess 48, so that when this embodiment is used for the original lock stitching, the loop released from the loop taker 41 and lifted by the takeup mechanism passes through the recess 48 exactly in the same manner as in the prior art lock stitch sewing machine, thus exerting no harmful effect on such stitching.

As mentioned above, the present invention provides a very advantageous chain stitch forming device for the general user of a sewing machine, thus widely broadening the application of an original lock stitch sewing machine.

What is claimed is:

1. A chain stitch forming device for a lock stitch sewing machine including
  - a frame having a work support perforated with a needle aperture,
  - a thread-carrying eyed needle supported by the frame above the work support for endwise reciprocation through the needle aperture,
  - a needle thread takeup mechanism mounted on the frame for alternately tightening and loosening the needle thread in timed relationship with the endwise reciprocation of the needle,
  - a loop taker so mounted on the frame as to rotate about an axis,
  - a bobbin case retainer supported in the loop taker and adapted to accommodate an ordinary bobbin case therein,
  - stop means provided between the frame and bobbin case retainer so as to prevent the bobbin case retainer from making a circular movement together with the loop taker near the point through which the needle passes endwise,

means for driving the needle and loop taker in such timed relationship that while the needle is brought down the loop coming out of the needle eye is seized by the loop taker and while the needle is lifted the seized loop is released from the loop taker, said stop means being provided with a recess and tongue connection freely engaging each other so as to form an opening therebetween for permitting the passage of the released loop pulled up by the needle thread takeup mechanism and,

means for linearly feeding a work fabric carried on the work support in a prescribed direction from the needle aperture during each endwise reciprocation of the needle, characterized in that the device further comprises

a movable loop retaining member having a retaining section for temporarily retaining the released loop pulled up through the opening by the thread takeup mechanism,

means connected to the loop retaining member for normally setting the retaining section of the loop retaining member in a loop retaining position above the opening so as to hold the released loop, and

operating means for moving the loop retaining member from the loop retaining position to allow the thread loop held on the retaining section to be pulled off therefrom by the thread takeup mechanism after the needle passes through the loop in the next downward movement.

2. A device according to claim 1 wherein the bobbin case retainer is provided with a projecting wall for guiding the released loop so as to securely hold it by the retaining section of the loop retaining member.

3. A device according to claim 1 wherein there is disposed between the operating means and loop retaining member means for controlling the time at which the loop retaining member is actuated by the operating means.

4. A chain stitch forming device for a lock stitch sewing machine including

a frame having a work support perforated with a needle aperture,

a thread-carrying eyed needle supported by the frame above the work support for endwise reciprocation through the needle aperture,

a needle thread takeup mechanism mounted on the frame for alternately tightening and loosening the needle thread in timed relationship with the endwise reciprocation of the needle,

a loop taker so mounted on the frame as to rotate about an axis,

a bobbin case retainer supported in the loop taker and adapted to accommodate an ordinary bobbin case therein,

a restraining member whose base end is fixed to the frame to prevent the bobbin case from making a circular movement together with the loop taker,

means for driving the needle and loop taker in such timed relationship that while the needle is brought down the loop coming out of the needle eye is seized by the loop taker and while the needle is lifted the seized loop is released from the loop taker,

a recess and tongue connection freely engaging each other positioned between the end of the restraining member and bobbin case retainer so as to form an opening therebetween for permitting the passage of the released loop pulled up by the needle thread takeup mechanism, and

means for linearly feeding a work fabric carried on the work support in a prescribed direction from the needle aperture during each endwise reciprocation of the needle, characterized in that the device further comprises

a loop retaining member rotatably mounted on the restraining member and having a loop retaining section formed at its free end for temporarily retaining the released loop pulled up through the opening by the thread takeup mechanism,

means connected to the loop retaining member for allowing the retaining section of the loop retaining member to be

normally set in a loop retaining position above the opening so as to hold the released loop, and operating means for moving the loop retaining member from the loop retaining position to allow the thread loop held on the retaining section to be pulled off therefrom by the thread takeup mechanism after the needle passes through the loop in the next downward moment.

5. A device according to claim 4 wherein there is provided stop means between the free end of the loop retaining member and restraining member so as to prevent said free end from being raised.

6. A device according to claim 5 wherein the free end of the loop retaining member is so bent as to surround the restraining member and contact the underside of the restraining member.

7. A chain stitch forming device for a lock stitch sewing machine including

a frame having a work support perforated with a needle aperture,

a thread-carrying eyed needle supported by the frame above the work support for endwise reciprocation through the needle aperture,

a needle thread takeup mechanism mounted on the frame for alternately tightening and loosening the needle thread in timed relationship with the endwise reciprocation of the needle,

a loop taker so mounted on the frame as to rotate about an axis,

a bobbin case retainer supported in the loop taker and adapted to accommodate an ordinary bobbin case therein, said bobbin case retainer being provided with a recess near the point through which the needle passes endwise, a restraining member having its base end fixed to the frame for preventing the bobbin case retainer from making a circular movement together with the loop taker and provided at the end with a tongue freely engaging the recess so as to define an opening therewith for permitting the passage of the released loop pulled up by the thread takeup mechanism,

means for driving the needle and loop taker in such timed relationship that while the needle is brought down the loop coming out of the needle eye is seized by the loop taker and while the needle is lifted the seized loop is released from the loop taker, and

means for linearly feeding a work fabric carried on the work support in a prescribed direction from the needle aperture during each endwise reciprocation of the needle, characterized in that the device further comprises

a movable loop retaining member having a retaining section for temporarily retaining the released loop pulled up through the opening by the thread takeup mechanism,

means connected to the loop retaining member for allowing the retaining section of the loop retaining member to be normally set in a loop retaining position above the opening so as to hold the released loop, and

means for moving the loop retaining member from the loop retaining position for allowing the thread loop held by the loop retaining section to be pulled off therefrom by the thread takeup mechanism after the needle passes through the loop in the next downward movement.

8. A device according to claim 7 wherein the bobbin case retainer is provided with a projecting wall for guiding the released loop in to the retaining section of the loop retaining member so as to securely hold it thereon, the top of said projecting wall being positioned below that part of the wall of the bobbin case retainer surrounding both sides of the tongue of the restraining member through which the needle passes endwise.

9. A device according to claim 7 wherein one side of the retaining section of the loop retaining member is so formed as not to project from one side of the tongue of the restraining member to which there is pressed the recess of the bobbin case retainer each time the loop taker rotates.

10. A device according to claim 7 wherein there is formed a groove at the top of the bobbin case retainer across the recess so as to extend toward both sides thereof and there is fitted

into the groove the retaining section of the loop retaining member.
